HYMAN F. CHAIKEN, Inventor

By Attorney

UNITED STATES PATENT OFFICE.

HYMAN F. CHAIKEN, OF READING, PENNSYLVANIA.

TOOTHBRUSH.

1,391,459.

Specification of Letters Patent. Patented Sept. 20, 1921.

Application filed January 21, 1921. Serial No. 438,839.

To all whom it may concern:

Be it known that I, HYMAN F. CHAIKEN, a citizen of the United States, residing at Reading, in the county of Berks and State 5 of Pennsylvania, have invented certain new and useful Improvements in Toothbrushes, of which the following is a specification.

This invention relates to improvements in tooth brushes, and the object in the present 10 instance is to provide in the first place, a thoroughly sterile brush.

Another object is to provide a brush which may conveniently be carried in the pocket, somewhat in the manner of a fountain pen, and in which this sterile condition 15 will be at all times maintained.

A further object is to provide means for carrying a supply of tooth paste or lotion within the container in which the brush is 20 carried.

A further object is to provide a removable handle which may serve as a closure for one compartment of the container, and also for a handle for the brush member.

The invention is more fully described in 25 the following specification and clearly illustrated in the accompanying drawing, in which:—

Figure 1 is a longitudinal sectional view 30 of my device with the relative parts in their proper positions, but with the closure cap for the sterilizing chamber open.

Fig. 2 is an outside, side elevational view 35 of my device.

Fig. 3 is a sectional view taken on line 3—3 of Fig. 1.

The numeral 1 designates a container, which may be made of hard rubber, or other like material, and which is formed of two 40 compartments, 2 and 3, both of which are open at one end. The compartment 2 is screw-threaded internally at its open end to receive the end of a screw threaded handle member 4. This handle member, in addition to the external thread 5, is also formed with an internal thread, for a purpose to be described later. This compartment 2 is intended to receive and hold a tooth paste tube or like article, 6, and the handle member 45 will serve, when in the position shown in the drawing, as a closure for this compartment.

The other compartment, 3, is designed 50 to receive and carry a tooth brush head 17, and in my present case I form this head with a threaded enlargement 8 at one end.

This brush head is carried in a receptacle 7, made of any suitable material, and adapted to fit loosely in the compartment 3, and to contain, beside the brush head, a sterilizing agent, preferably in the form of a granulated substance, designated by the numeral 11. The receptacle 7 is open at one end, and when in position in the compartment 3, it will reach almost to the edge of the compartment, and I provide a closure for both the compartment 3 and the receptacle 7, in the form of a single cap 12, attached to the container 1 by means of a hinge 13 and provided with a catch 14 for holding it in 60 closed position. This cap bears against the end of the container and closes the compartment 3, and it is formed with a lug 15 adapted to enter the open end of the receptacle 7 and form a closure therefor. 65

The brush head is normally carried in the container, as illustrated, and when it is desired to use it, the cap is opened, and the brush head removed. The handle 4 is removed from its engagement with the container compartment 2 and the enlarged screw-threaded end 8 of the brush head is inserted in the internally screw-threaded end 18 of the handle member, when it will be ready for use; and, the act of removing 80 the handle from the container, at the same time exposes the tooth paste tube which may be dropped out ready for use. 85

The extreme utility of the device is of course evident, and of some consequence, but 90 the most important feature of the invention is the fact that I have provided a tooth brush that will be kept sterile at all times, because after using it, the moisture still adhering to the brush will be absorbed by the 95 sterilizing agent at the same time that the brush is being sterilized.

The respective parts may be made of any suitable material and shape, but I have shown it in a preferred form, suitable for 100 carrying in a vest pocket.

Having thus fully described my invention, what I claim and desire to secure by Letters Patent is:—

1. A tooth brush comprising a screw-threaded handle member, a screw-threaded brush head, both substantially as described, in combination with a container formed in two compartments, one of which is adapted to receive the handle member and the other 105 the brush head, said handle member forming a closure for the compartment into 110

- which it enters, a receptacle containing a sterilizing agent for housing the brush head while in the compartment and a closure for both the receptacle and the compartment.
5. 2. In a device of the character described, the combination of a two-part tooth brush, with a container formed in two compartments, one of which is provided with a removable receptacle adapted to hold a sterilizing agent and the brush head, a cap hinged to the container and adapted to close both the removable receptacle and the compartment in which the receptacle is located; the other compartment being screw-threaded and adapted to receive the end of handle portion of the two part brush, said handle being also screw-threaded to receive the end of the brush head.
3. The combination of a casing made in 20 two compartments, each of which is adapted

to receive a container, one compartment being provided with a closure cap adapted to close the compartment and its container at the same time, with a two part tooth brush the handle portion of which forms a closure 25 for the other compartment while the brush head is located within the container in the first named compartment.

4. A self sterilizing tooth brush comprising a two part brush, a container for the brush head, a sterilizing agent within the container, a receptacle or casing for the container, a closure for the container, means in the casing for carrying a supply of tooth paste and means for holding the tooth paste 30 in the casing comprising the handle member of the tooth brush.

In testimony whereof I affix my signature.

HYMAN F. CHAIKEN.
